UNITED STATES PATENT OFFICE.

GEORGE M. BROUS, OF PORTLAND, OREGON.

MACHINE FOR FORMING TIE-WIRES.

1,315,083.

Specification of Letters Patent.

Patented Sept. 2, 1919.

Application filed April 24, 1918. Serial No. 230,491.

To all whom it may concern:

Be it known that I, GEORGE M. BROUS, a citizen of the United States, residing at Portland, in the county of Multnomah and 5 State of Oregon, have invented a new and useful Machine for Forming Tie-Wires, of which the following is a specification.

This invention has reference to machines for forming tie wires, and its object is to 10 automatically and rapidly produce a closed loop at the end of the wire and then sever the wire with the formed loop from the next succeeding length of wire, whereby each tie wire comprises a straight length of wire of 15 suitable extent with a closed loop at one end thereof.

In accordance with the invention there is provided a twisting head orbitally revolving in a path, the diameter of which determines 20 the length of the finished tie wire, with each completed tie wire severed from the next succeeding one as soon as the end loop of said succeeding tie wire is completed, the operation being continuous and the tie wire 25 being completed and discharged from the machine on each complete orbital movement of a twisting head, the machine comprising two twisting heads on the opposite sides of the axis of rotation.

30 The machine is provided with a holder for a reel of wire and aside from the initial threading of the machine the operation is entirely automatic, the loop in the end of the wire being formed at a point opposite from 35 the feeding-in side of the machine and such loop end being carried, in the progressive movement of the twisting head forming the loop, to a point adjacent to the feeding-in side of the machine, and as soon as the next 40 succeeding loop is produced the length of wire with the first formed loop is severed from the wire on which the second loop is produced at said second loop and the completed tie wire with a loop at one end is 45 then automatically discharged from the machine.

The invention will be best understood from a consideration of the following detailed description taken in connection with 50 the accompanying drawings forming part of this specification, with the understanding, however, that the invention is not confined to any strict conformity with the showing of the drawings but may be changed and modified 55 so long as such changes and modifications mark no material departure from the

salient features of the invention as expressed in the appended claims.

In the drawings:—

Figure 1 is a front elevation of a machine constructed in accordance with the invention and illustrating in full lines the initial step of the operation and in dotted lines another position of the twisting heads 60 of the machine.

Fig. 2 is a vertical diametric front to rear section of the machine showing the rotor but omitting the twisting heads and distant parts.

Fig. 3 is a rear elevation of the machine. 70

Fig. 4 is a plan view of one of the twisting heads and adjacent portions of the frame and rotor.

Fig. 5 is a detail elevation of a portion 75 of the structure shown in Fig. 4 as viewed from the right hand side thereof.

Fig. 6 is a section on the line 6—6 of Fig. 4 with the twisting head driving pinion in mesh with a rack carried by the main frame.

Fig. 7 is a detail view showing a wire- 80 severing device with some parts in section.

Referring to the drawings, there is shown a main frame 1 conveniently made of circular outline with a peripheral strengthening rib 2, a central hub 3 and supporting legs 4, 85 all of which may constitute parts of a single casting, although such particular construction is not obligatory. The hub 3 constitutes or carries a journal for a shaft 5 also having journal bearings 6, on the upper end of a post 7 provided with a base 8 made fast to the lower portion of the frame 1 by screws 9 or otherwise, the base 8 and the legs 4 being utilized for fastening screws or bolts 10 for securing the machine to a floor or other 90 like support.

Mounted in journal bearings in spaced brackets 11, 12 on the rear face of the frame 1 is a countershaft 13 carrying a pulley 14 by means of which power may be applied to 100 the shaft 13 and from which shaft, by means of a power transmitting belt 15, another countershaft 16 is driven, this countershaft having journal bearings 17, 18 on the rear of the frame 1. The countershaft 16 carries a bevel pinion 19 meshing with the bevel gear wheel 20 on the shaft 5. In this manner the shaft 5 is driven from a source of power at an appropriate speed, no attempt having been made in the drawings to 105 indicate any particular speed, such speed depending upon the prime mover or other 110

conditions and the ratio of power transmission being subject to change as found expedient.

The shaft 5 projects through the front of 5 the main frame and there carries a disk 21 surrounded and backed up by an annular ledge 22 in turn surrounded by an annular flange 23 adjacent to the periphery of the disk 21 and provided at certain points with 10 depressed portions 24 and 25 for purposes which will hereinafter appear. The flange 23 constitutes a track and the internal diameter is greater than the diameter of the rotor.

15 The ledge 22 and flange 23 may be conveniently formed in one piece with the main frame 1 or may be separately formed and attached thereto, these being constructional details subject to variations.

20 The disk 21 constitutes a rotor on which at diametrically opposite points are mounted twisting heads or devices 26, 27 respectively, these twisting heads being identical and only 25 separately designated to facilitate the description of the operation of the machine. The twisting heads being alike, a description of one will apply to both. Each comprises a U-shaped frame or yoke 28 which, together with other parts, is best shown in 30 Fig. 4. Each twisting head is located in a depression or opening 29 in the disk or rotor 21 adjacent to the periphery of the rotor with the depressions diametrically opposite and receiving respective ones of the 35 twisting head 26 and 27, these twisting heads as a whole being about flush with the face of the disk or rotor. The depressions 29 are provided with side ledges 30 each having a series of perforations 31 for receiving screws or bolts 32, extending through 40 legs 33 constituting the opposite legs of the yoke 28, permitting the adjustment of the yoke or frame 28 radially of the rotor so that, as will hereinafter appear, a consider- 45 able variation in the lengths of the tie wires is possible. At the closed end of the frame 28 there is a journal bearing 35 traversed by an arbor 36 and carrying the latter, the arbor having set collars 37 thereon permitting 50 a degree of adjustment of the arbor 36 radially with respect to the rotor 21. On the arbor on the side of the journal bearing 35 remote from the axis of rotation of the rotor is a roller 38 having peripheral flats 55 39 in angular relation, which relation in the particular instance shown is a right angular relation. Housed within the journal bearing 35 and fast to the arbor 36 is a gear pinion 40 traveling in overriding relation to the ledge 22 and at those portions of the ledge 22 corresponding to the depressed parts 24 and 25 of the flange 23 are segmental rack bars 41 and 42 respectively, the rack bar 41 being of a length to actuate the 60 pinion 40 to cause a predetermined number

of rotations of the pinion 40 and arbor 36 with it. The length of the rack bar 42 is such as to cause a quarter rotation of the arbor 36 when the rack bar engages the pinion 40, such quarter rotation of the arbor 70 36 bringing one or the other of the flats 39 into parallelism with the outer edge of the flange 23, which flange serves as a track, preventing any rotation of the arbor 36 while a flat 39 is riding thereon. In order 75 to permit the roller 38 to turn, the depressed portions 24 and 25 of the flange 23 are provided, wherefore, the flange 23 offers no impediment to the rotation of the pinion 40 and with it the arbor 36 while the rack bars 80 24 and 25 are in engagement with the pinion 40.

At the end of the arbor 36 toward the center of the disk or rotor 21 there is secured a collar or head 43 carrying a bent finger 44 with its point of connection with the head or collar 43 eccentric to the axis of rotation of the arbor and this finger 44 extends diametrically across the head 43 in spaced relation thereto and beyond that side of the head remote from the point of attachment of the finger 44 with the head, the free end of the finger being preferably pointed. At certain phases of the operation of the machine the finger end of the arbor 36 is subjected to side strain and in order to resist such side strain a thrust member 45 is attached to one leg of the frame 28 and has a forked free end 46 bearing against one side of the arbor 36.

Beyond the ends of the legs 33 remote from the joined ends thereof is a bar 47 which may be adjusted along the ledges 30, because of the series of perforations 31, and erected on this bar 47 is a post 48 made quite thin in the direction of the length of the bar but which may be made as wide as the bar for strength. Pivoted to the bar 47 at one side thereof is a shear blade 49 in position to coact with the post 48 for a purpose which will presently appear. The pivot support for the shear blade may be in the form of a screw 50, or other pivotal means may be used, and projecting on the side of the pivot 50 remote from the shear blade is 110 an arm 51 having at its end a roller 52.

The frame 1 at an appropriate point has a cam projection 53 in the path of the roller 52 so that at a proper time in the orbital movement of the roller 52 it is brought into engagement with the cam 53, thereby causing a rocking of the shear blade into operative relation to the post 48. The shear blade 49 is held in a normally inactive position by a spring 54.

Fast to that side of the frame near the rack 42 is a carrier 55 for a reel 56 of wire 57. The carrier 55 is provided with a presser arm 57^a for engaging the reel 56 and serving as a friction member or brake, 130

causing the reel to rotate to pay out the wire under some tension.

On the frame 1 adjacent to the carrier 55 is secured a bracket 58 to which is pivotally mounted at an intermediate point of its length, by a pivot bolt 58^a, a rockable tension clamp 59 having clamping parts and screws 60 permitting the degree of tension to be regulated as desired. The wire 57 is threaded through the tension device or clamp 59, across the disk 21 to a twisting head then located on the opposite side of the machine, say the twisting head 26, as shown in Fig. 1. The free end of the wire 57 is formed by hand into a loop and applied to the finger 44 of the twisting head 26. On the trailing side of the post 48, the tension clamp 59 holds the wire sufficiently taut to prevent it from falling from the finger 44. Now, as the disk or rotor 21 is caused to move in the direction of the arrow in Fig. 1, that is counter-clockwise, the twisting head 26 carries the wire 57, then fast to the twisting head 26 in a direction which will cause it to sweep across the center of the disk 21. However, at the same time the twisting head 27 is traveling and ultimately the post 48 thereof engages the wire 57 and carries the wire with it until that portion of the wire toward the twisting head 26 and the portion of the wire toward the intake of the machine are folded upon themselves with the bight of the wire engaging about the post 48 of the twisting head 27. Because of the presence of the short rack 42 the finger 44 is then outstanding from the disk 21. In order to insure that the outstanding finger 44 properly engages the strand of wire 57 then in the path of the finger, there is provided a support 61 extending outwardly from the main frame 1 at a higher point than the reel support 55 and this support 61 carries a bar 62 adjustable in a direction about radial to the disk 21. The bar 62 serves as a support for a curved arm 63 having a roller 64 at its extremity in position to override the wire 57 then across the disk 21 and reaching to the opposite twisting head 26. The arm 63 has a continuation 65 in the form of a head suitably shaped to engage and force the finished tie wires from the fingers 44. The discharge is facilitated by springs 66 on the bars 47, to which springs reference will hereinafter be made. The roller 64 serves to hold the wire 57 close enough to the disk 21 to insure engagement with the wire by the fingers 44 and may be termed a hold-down device.

After the wire has had a preliminary loop 67 formed in it and engaged over a respective finger 44 and the machine is started in operation, the preliminary loop 67 is ultimately brought to a position about that shown in Fig. 1 as the position of the twisting head 27. While this condition is being approached the pinion 40 of the twisting head 27 has reached the rack 41, at which point the active flat on the roller 38 is at the recess 24. As the twisting head 27 travels over the rack 41 the portion of the two wires between the rotating finger 44 and the post 48 are twisted together with the two strands of wire straddling the post 48. This occurs before the pinion 40 on the head 26 reaches the rack 42. Also before the pinion 40 reaches the rack 42 the cam 53 engages the roller 52 and actuates the cutter-head 49 against the tendency of the spring 54 to shear off the strand of wire 57 on the forward side of the post 48, whereupon, the completed strand, or the one having the preliminary twist loop 67, as the case may be, is cut off from the twisting head previously holding it, leaving the strand connected to the machine only at the finger 44, then adjacent to the entering end of the machine. When that end of the wire strand remote from the formed loop is cut off, the head 65, which serves as a stripper, engages the loop and strips it from the finger 44 carrying it, such finger at the time being in trailing relation or pointing in a reverse direction to the direction of travel of the twisting head. The stripping action is facilitated by the springs 66, which on release from pressure, under which they are initially put by the wire 57, throw the wire when stripped from the finger away from the face of the rotor 21 so that the wire may fall free of the machine and into a suitable receptacle, the latter, however, not being shown. The preliminarily twisted loop 67 is formed by hand but thereafter the wire is twisted into automatically formed twisted loops 67^a, as shown in Fig. 4.

After the machine has been started and the strand with the preliminarily formed loop has been discharged from the machine, the operation proceeds entirely automatically. The finger 44 on each twisting head as it approaches the entering side of the machine points rearwardly with respect to the line of travel until the formed loop is stripped therefrom, whereupon, with the parts properly timed, the pinion 40 is brought into contact with the short rack 42 and a quarter turn is imparted to the arbor 36, thus causing the finger 44 to stand outwardly from the disk or rotor 21 so as to be perpendicular thereto and in position to engage the wire 57 then in its path, the wire being held toward the disk 21 by the roller 64. As the forward movement of the rotor 21 progresses the wire is looped with the bight on opposite sides of the post 48 and while in this condition the pinion 40 comes in contact with the longer rack 41, whereupon, the twist 67^a, Fig. 4, is produced. As soon as the proper flat 39 is brought into engagement with the

flange 23 after passing the rack 41, the cam 53 becomes active to move the shear or cutter 49 to sever the forward strand of wire 57 from the rearward strand in order of travel and from the adjacent loop produced immediately previously by the appropriate twisting head 26. At about the same time the loop at the other end of the cut strand and located near the entering end of the 10 machine is stripped from the finger 44 carrying it, said finger being then moved from substantial parallelism with the disk 21 into perpendicular relation thereto by the action of the short rack 42 on the pinion 40. 15 The long rack is designed to cause enough turns of the twisting finger 44 to produce a safe twist in the wire capable of withstanding the strains to which the wire is subjected without any liability of pulling out. 20 The short rack need only be long enough to cause a quarter turn of the twisting finger, such movement being inactive so far as twisting the wire is concerned.

The loops and twists are all alike but the 25 length of the wire formed into a tie wire may be varied by adjusting the twisting heads toward or from the axis of movement of the rotor. The finished product is a substantially straight wire of such length as 30 may be desired with one end formed into a closed loop with a twist preventing the loop from pulling out.

What is claimed is:

1. In a machine of the class described, a 35 main frame with an annular ledge surrounded by an annular flange forming a track, segmental racks provided on the ledge, said flange being depressed at points coincident with the racks, a rotor concentric with the flange and of less diameter than the ledge and track, twisting devices 40 arranged diametrically opposite each other and radially disposed on the rotor adjacent the periphery thereof, a portion of each 45 twisting device projecting beyond said periphery, said twisting devices each having a pinion to engage the racks in succession as the rotor is revolved, and a roller rotatable with the pinion and engaging the flange.

2. In a machine for forming tie wires from continuous strands of wire with each tie wire having a twisted loop at one end, an upright main frame with a circular track thereon having its continuity broken at approximately opposite points, a rotor carried 55 by the main frame and rotatable upon a substantially horizontal axis concentric with the track, twisting heads carried by the rotor on opposite sides of the axis of rotation, twisting hooks carried by the twisting heads and each provided with a pinion and with a roller, said roller having peripheral flats movable along the track in engagement therewith, the said twisting hooks 60 having their active ends radial to their axis 65

of rotation, and racks associated with the portions of the track where its continuity is broken, with one rack of a length to impart a partial turn to the hook and the other rack of a length to impart a plurality of 70 turns to the hook.

3. In a machine of the class described, a main frame with an annular track within its margin, said track having its continuity broken at intervals, segmental rack bars 75 on the main frame at the points where the continuity of the track is broken and located interior to and beside the track, a single rotary disk interior to and concentric with the rack bars and track, a pair of twisting 80 heads mounted at opposite sides of the outer face of the disk, and each provided with a pinion projecting from the periphery of the disk for engaging the racks, and a peripherally flattened roller also projecting from 85 the edge of the disk for engaging the track, a twisting hook fast to the pinion and roller, and cutting means for the wire carried by each twisting head.

4. In a machine of the class described, a 90 main frame, a rotor with recesses on opposite sides of the axis of rotation, each recess having side ledges, and twisting heads 95 each provided with a supporting yoke the legs of which are carried by and adjustable radially of the rotor along the ledges, and each head having an arbor rotatably mounted therein and extending radially of the rotor and independently radially adjustable, said arbor having a hook-shaped 100 finger mounted at its inner end.

5. In a machine of the class described, the combination with a main frame, a rotor having radial depressions leading in from its periphery, said depressions having side 105 ledges, twisting heads mounted in said depressions, each head having a yoke the legs of which are mounted upon said ledges, means for adjustably connecting said legs to said ledges to permit the radial adjustment 110 of said heads, a transverse bar separate from the yoke having its ends adjustably connected to said ledges, and cutting mechanism carried by said bar.

6. In a machine of the class described, a 115 twisting head including an arbor, a collar secured to the arbor, a bent and pointed finger carried by the collar at a point eccentric to the axis of rotation of the arbor, said finger extending diametrically across said 120 collar in spaced relation to the same, being thereby disposed substantially radial to the axis of twisting.

7. In a machine of the class described, a 125 twisting head including an arbor, a collar secured to the arbor at the inner end thereof, a bent and pointed finger mounted on the collar at a point eccentric to the axis of the arbor, said finger extending diametrically across and beyond said collar in spaced 130

- relation thereto, said arbor being adjustable longitudinally on the twisting head.
8. In a machine of the class described, a frame, a rotor, a twisting head on the rotor, said twisting head including a yoke radially adjustable on the rotor, an arbor radially adjustable on the yoke, and a wire-engaging post adjustable with respect to the rotor.
9. In a machine of the class described, a frame, a rotor, a twisting head on the rotor, said twisting head including a bar having an upstanding post, and a wire-cutting element in coöperative relation to said post carried by said bar, said bar being adjustable with respect to the rotor and the elements of the twisting head whereby the position of the cut may be varied.
10. In a machine of the class described, a frame, a rotor, a twisting head on the rotor, said twisting head including a bar, a post extending outwardly from the bar, a cutting device to one side of the bar and connected thereto and coöperating with the post, and a spring throw-off device on the other side of the bar whereby the wire when cut is removed from the head.
11. In a machine for forming tie wires from a continuous strand of wire with each tie wire at one end twisted into a closed loop, a main frame, a rotor mounted on the main frame and having recesses on opposite sides, a twisting head in each recess, said twisting head including a rotatable arbor and a finger on the arbor for engaging and twisting the wire, a bar extending crosswise of the recess and provided with an outstanding post adjacent to the finger and between which post and finger the wire is twisted by rotating the arbor, a shear blade mounted on the bar in operative relation to the post for severing a preceding portion of the wire from the twist, and means on the fixed part of the machine for operating the shear blade at a predetermined point in the rotation of the rotor.
12. In a machine for forming tie wires from a continuous strand of wire with each tie wire at one end twisted into a closed loop, a main frame, a rotor mounted on the main frame and having recesses on opposite sides, a twisting head in each recess, said twisting head including a rotatable arbor and a finger on the arbor for engaging and twisting the wire, a bar extending crosswise of the recess and provided with an outstanding post adjacent to the finger and between which post and finger the wire is twisted by rotating the arbor, a shear blade mounted on the bar in operative relation to the post for severing a preceding portion of the wire from the twist, and means on a fixed part of the machine for operating the shear blade at a predetermined point in the rotation of the rotor, the bar with the post thereon also hav-
- ing springs for underlying the wire strand to throw or kick off the wire.
13. In a machine for forming tie wires from a continuous strand of wire, a main frame, a rotor with twisting heads thereon, and a tension device for wire fed to the twisting heads, said tension device being carried by the main frame and comprising a bracket rigidly mounted on the main frame, and a clamp pivotally mounted at an intermediate point between its ends upon the bracket and thereby made rockable, said clamp having clamping parts for gripping the wire with predetermined pressure.
14. In a machine for forming tie wires from a continuous strand of wire with each tie wire at one end twisted into a closed loop, a main frame, a rotor mounted thereon, twisting heads carried by the rotor on opposite sides of the center thereof, and a hold-down device carried by the main frame in the path of the wire extending across the rotor and adjustable radially with respect to the rotor.
15. In a machine of the class described, a frame, a rotor, a twisting head on the rotor, and a hold-down device carried by the frame, said device including a support, a bar slidably adjustable in the support, an arm extending at an angle from the end of the bar, and a roller adapted to be engaged with the wire to be twisted and hold the same for engagement by the twisting head.
16. In a machine for forming tie wires from a continuous strand of wire, a main frame, a rotor mounted on the frame, twisting heads on said rotor, and a hold-down device carried by the frame in the path of wire extending over the rotor, said device including an arm, and a roller mounted on said arm to override the wire and hold the same sufficiently close to the rotor to insure engagement with the wire by one of the twisting heads.
17. In a machine for forming tie wires from a continuous strand of wire with each tie wire at one end twisted into a closed loop, a rotor with twisting heads thereon for the wire, a main frame surrounding the rotor, a support on the main frame, a stripper on the support in position to engage a formed loop on a twisting head and discharge the loop therefrom, and springs associated with the twisting heads to force the completed tie wire out from the machine.
18. In a machine for forming tie wires from a continuous strand of wire with each tie wire at one end twisted into a closed loop, a rotor with twisting heads thereon for the wire, a main frame surrounding the rotor, a support on the main frame, and a stripper on the support in position to engage a formed loop on a twisting head and dis-

charge the loop therefrom, the support also carrying a depressing member in spaced relation to the stripper for engaging and holding down wire in the path of the twisting head from which a wire loop has been stripped.

In testimony, that I claim the foregoing

as my own, and have hereto affixed my signature in the presence of two witnesses.
